(57) **CLAIM**

The ornamental design for a mesh tray, as shown and described.

DESCRIPTION

FIG. 1 is a front perspective view of a mesh tray;
FIG. 2 is a front view of the mesh tray of FIG. 1;
FIG. 3 is a side elevation view of one side of the mesh tray of FIG. 1;
FIG. 4 is a side view of the mesh tray of FIG. 1;
FIG. 5 is a top perspective view of the mesh tray of FIG. 1;
FIG. 6 is an enlarged detail view of area 6 circumscribed within the mesh tray of FIG. 5;
FIG. 7 is a bottom perspective view of the mesh tray of FIG. 1;
FIG. 8 is a perspective view of a mesh tray of FIG. 1 in a use configuration with environment; and,
FIG. 9 is a perspective view of a mesh tray of FIG. 1 in a use configuration with environment.
The dot dash broken lines in FIGS. 5 and 6 denote the boundaries of the enlargements that form no part of the claimed design. The evenly spaced broken lines in FIGS. 8 and 9 depict environmental subject matter that forms no part of the claimed design.

1 Claim, 7 Drawing Sheets
